UNITED STATES PATENT OFFICE.

ISIDOR TORNBERG, OF PLAINFIELD, NEW JERSEY.

COMBINED CHECK PROTECTOR AND BLOTTER.

Application filed January 2, 1923. Serial No. 610,398.

To all whom it may concern:

Be it known that I, ISIDOR TORNBERG, a citizen of the United States, and a resident of Plainfield, in the county of Union and State of New Jersey, have invented certain new and useful Improvements in or Relating to Combined Check Protectors and Blotters, of which the following is a specification.

10 The invention relates to a check protector and blotter adapted for the individual immediate use of a person drawing a bank check, enabling such person to dry the ink on the check with the use of the blotter and then protect the figures or writing, or both, by puncturing the check in the zones of such figures or writing.

One object of the invention is to produce an efficient article for the purposes specified, 20 which shall be convenient of use and of such inexpensive nature that a bank can afford to give the same to its depositors, especially when the article bears, as it may, the advertisement of the bank. The article of my 25 invention may be folded into or closed within a check book, so as always to be handy for use, and the article serves as a convenience when a check is drawn in that it provides a blotter and means to guard against 30 the alteration of the check, thereby protecting both the drawer of the check and the bank on which the check is drawn.

In carrying out my invention I provide a blotter of appropriate size for blotting the 35 writing on a bank check and on one face of the blotter I firmly secure a strip or plate of thin flexible sheet metal having its surface corresponding with the zones of the writing on the check, covered with small 40 punctures, the burrs formed at the punctures being exposed upwardly and forming a surface of cutting edges adapted when a check is held over and rubbed downwardly against the same to sufficiently perforate the check 45 to render alteration of the writing thereon, without detection, extremely difficult. The blotter serves several purposes, one being to dry the ink on a check, another to carry the check protector plate and another to provide 50 a cushion-backing for the protector and against which the protector is pressed when a check is being held over and rubbed downwardly against the protector, the cushion at this time aiding the thin protector plate in the performance of its functions.

55 The invention will be fully understood

from the detailed description hereinafter presented, reference being had to the accompanying drawings, in which:

Fig. 1 is a perspective view of a combined check protector and blotter constructed in accordance with and embodying my invention;

Fig. 2 is an end view, on a larger scale, of the same;

Fig. 3 is a vertical section, partly broken away and on an enlarged scale, through the same, taken on the dotted line 3—3 of Fig. 1 and illustrating, by dotted lines, a check in position on the protector for puncturing the necessary portions of the same;

Fig. 4 is a perspective view of a modified form of check protector and blotter embodying my invention;

Fig. 5 is a rear view of one corner portion of the same;

Fig. 6 is a perspective view of a combined check protector and blotter having the features of the device shown in Fig. 1, but formed to be used in a pocket check-book having folded checks;

Fig. 7 is a front view of a portion of a modified form of check protector and blotter;

Fig. 8 is a vertical section through the same, taken on the dotted line 8—8 of Fig. 7, and

Fig. 9 is a top edge view, partly broken away, of a further combined check-protector and blotter embodying certain features of my invention.

In the drawings, referring to Figs. 1, 2 and 3, I show a combined check protector and blotter of the construction preferred by me, and therein 10 designates a sheet of absorbent blotting paper of good quality and reasonably soft texture and of convenient elongated shape for use in covering and blotting a check, 11 a thin flexible strip or sheet of metal suitably positioned lengthwise on said blotter between the upper and lower edge portions of the same; 12 a strip of paper or the like glued or otherwise secured to and covering the face of the blotter above the metallic strip 11 and lapping upon the upper edge portions of said strip, and 13 a strip of paper or the like glued or otherwise secured to and covering the face of the blotter below the metallic strip 11 and lapping upon the lower edge portions of said strip. The facing edge portions of the strips 12, 13 serve to secure the strip 11

upon the blotter 10 but said strip may be additionally secured to the blotter 10 by additional means, as will be understood from other portions of this specification. In the construction shown in Figs. 1, 2 and 3, I apply the strip 11 upon the blotter 10 and then glue the paper strips 12, 13 upon the blotter and edge portions of the strip 11.

The strip 11 is a section of a thin metallic ribbon and is so positioned on the blotter 10 that when a bank check has been written upon and placed, with its face down, upon the article of my invention, the line of writing on the check will be upon the length 15 of the strip 11. The strip 11 is closely punctured over its entire or any appropriate portion of its surface, the punctures creating sharp edged burrs 14 which project upwardly and thus become exposed to receive and puncture the check along the zone or zones thereof bearing the writing, as represented in Fig. 3, wherein a check pierced by the burrs 14 is indicated by the dotted lines 15.

25 The paper strips 12, 13 impart durability to the blotter 10 and increase the period of usefulness of the same, and in addition said strips afford adequate surfaces to receive advertising matter, as shown, it being intended 30 that the face of my article shall bear the advertisement of a bank and be in the general form or similitude of a bank check.

In the use of the article described, the blotter 10 will be made use of to blot or dry 35 the ink on a check as drawn, and thereupon the check will be placed, face down, upon the article with the writing thereon superposed upon the strip 11, after which the drawer will rub his hand or fingers with a 40 down-pressure against the back of the check so as to cause the face of the check to be punctured or cut by the burrs 14, said burrs sufficiently mutilating the check to prevent alteration of the writing thereon without 45 detection. The strip 11 is thin and flexible and the blotter 10 provides a yielding cushion or base for the strip 11, and hence the article is yieldable to vertical pressure and the drawer of the check may rub the check 50 over the strip 11 without danger to his hands and obtain an efficient action of the burrs 14 on the check.

The article as a whole is designed to be carried in a pocket check book so as always 55 to be handy for immediate use.

In Figs. 4 and 5 I show a construction of the article in which the blotter, numbered therein 16, is entirely covered over on one face by a thin flexible metallic plate 17 60 whose corner portions 18 are bent over on the adjacent portions of the blotter and secure the blotter and plate together, said portions 18 serving as clips and permitting a renewal of the blotter whenever necessary. 65 The plate 17 will be punctured over a proper

zone 19 to serve for puncturing the checks in the manner and for the purposes hereinbefore explained, the zone 19 having the same punctures hereinbefore described with reference to Figs. 1, 2 and 3. In the form of the 70 invention shown in Figs. 4 and 5, the advertising matter will be applied directly upon the plate 17 by the art of printing, embossing or other convenient method. The construction shown in Figs. 4 and 5, is very desirable in that the plate 17 fully protects one face of the blotter and permits of the renewal of the blotter from time to time until the plate itself has ceased to be useful. 75

The construction of the article shown in 80 Fig. 6 corresponds with the construction shown in Figs. 1, 2 and 3, except that I form the body thereof with a central vertical fold-line or crease 19' and the punctured strip in two sections 20, 21, so as to render the combined blotter and check protector foldable and adapt the same for the popular pocket check books having folded checks. 85

I present Figs. 8 and 9 to indicate that the punctured strip 22 may be fastened to 90 the blotter 23 by staples, eyelets or spurs 24 formed from the strip 22 and forced through and bent over against the blotter, this method of securing the strip being applicable to the strips shown in Figs. 1 and 6 and also 95 to the plate shown in Fig. 4.

In the construction shown in Fig. 9, the punctured strip 25 is normally longer than the blotter 26 and its ends are folded over and under and pinch the blotter, as at 27, 100 and this method of securing the strip may be followed with respect to the constructions shown in the other figures of the drawings.

In all of the constructions shown I present a portable combined check protector 105 and blotter adapted to be closed within a check-book and to be efficiently used in the manner hereinbefore described.

What I claim as my invention and desire 110 to secure by Letters Patent, is:

1. As a new article of manufacture, a combined check protector and blotter comprising a sheet of blotting paper adapted on one face for blotting the writing on a bank check and being approximately of check 115 outline, and a thin flexible metallic strip or sheet secured against the other face of the blotter and punctured to form closely grouped outstanding burrs in a zone adapting the burrs to receive and puncture the 120 writing on a check when the check is pressed downwardly against said burrs, said strip or sheet being extended the full length of said blotter.

2. As a new article of manufacture, a 125 combined check protector and blotter comprising a sheet of blotting paper adapted on one face for blotting the writing on a bank check and being approximately of check outline, a thin flexible metallic strip or sheet 130

extending lengthwise upon the other face of the blotter and strips secured upon said other face of the blotter above and below said metallic strip or sheet and lapping upon the upper and lower edge portions of the same for securing the metallic strip or sheet in place, said metallic strip or sheet being punctured to form closely grouped outstand-

ing burrs in a zone adapting the burrs to receive and puncture the writing on a check 10 when the check is pressed downwardly against said burrs.

Signed at Plainfield, in the county of Union and State of New Jersey, this 29th day of December A. D. 1922.

ISIDOR TORNBERG.
